UNITED STATES PATENT OFFICE.

HORACE TURRETTINI, OF GENEVA, SWITZERLAND.

HEATING DEVICE.

1,321,574.

Specification of Letters Patent. Patented Nov. 11, 1919.

Application filed May 22, 1918. Serial No. 235,995.

To all whom it may concern:

Be it known that I, HORACE TURRETTINI, gentleman, a citizen of Switzerland, residing at Geneva, Canton of Geneva, in the 5 Confederation of Switzerland, have invented certain new and useful Improvements in or Relating to Heating Devices, of which the following is a specification.

This invention relates to a heating apparatus and more particularly to that type of heating apparatus in which lime or other similar substances are so employed that by the action of water thereon, the heat generated is utilized in any suitable manner for 10 heating a receptacle which, after receiving the heat, may be employed for any desired purpose. The invention relates more particularly to the manner in which the heat cartridge is formed so as to prevent the lime or other material in expanding from so enlarging the cartridge that the cartridge may not be readily removed from the receptacle or container in which it is utilized, and furthermore, the cartridge is so constructed 15 that in the use thereof both in inserting and removing the cartridge from the receptacle, the hands of the user will not be soiled. The heating apparatus made in accordance with my invention will be hereinafter more particularly described.

Figure 1 is an elevation illustrating a device consisting of a porous packet containing unslaked lime and provided with inextensible bands arranged to maintain the 20 packet in shape when the lime expands so that the packet may be readily removed from a casing.

Fig. 2 is a sectional elevation showing the packet as illustrated in Fig. 1 contained 25 within a casing and illustrating the shape the packet assumes after the unslaked lime has expanded.

Fig. 3 is an elevation of a modified form of casing, and

Fig. 4 is a side elevation of the casing shown in Fig. 3 illustrating the closure of the casing after having been disengaged.

Referring to the drawing and more particularly to Figs. 1 and 2, the packet of lime 30 contained in a porous envelop, shown in Fig. 1, and intended for the cylindrical warmer shown in Fig. 2, is provided with a certain number of inextensible bands e^1 , such for example, as twine. When this packet is introduced into the cylindrical metal case a (Fig. 2) containing water, the latter pro-

duces an expansion of the lime and of the porous casing; owing to the bands e^1 , this expansion is spread over the packet e , so that, as soon as the lime expands, the packet 60 assumes the shape shown in Fig. 2 which facilitates the removal of the packet from the case a as soon as the cover a^1 is removed.

In the construction shown in Figs. 3 and 4, the rectangular heater a is provided with 65 a tightly closing cover a^1 held in place by means of a closure f connected to the cover by rods g hinged to the said cover and provided with screws h screwed into the closure. The ends of the latter are each provided 70 with a hook f^1 intended to engage with an inclined plane a^2 of a lateral projection of the case a . The said shackle f is moreover made of such a shape as to enable it to be used as a handle for carrying the heater. 75 The cover a^1 is provided with a spring-controlled safety valve i intended to become operative in the event of the expansion of the lime, air and steam producing an excessive pressure in the case a . The lime 80 packets e can be constituted by one or more casings of porous fabric or paper.

These porous casings containing lime, can be handled without dirtying the fingers, and moreover they prevent the lime from adhering to the inner walls of the metal case, 85 so that it is not necessary to clean them.

I claim as my invention:

1. As a new article of manufacture, a heater comprising a receptacle, a cover removably connected thereto and a cartridge adapted to be placed in the casing and comprising a wrapper of porous material, a filling of unslaked lime, and a plurality of bands in spaced positions extending around said 90 cartridge and dividing the same into sections so as to prevent the expansion of the cartridge beyond predetermined limits and to maintain the same in substantially cylindrical form while in use so that it may be 95 readily removed after use from the receptacle.

2. As a new article of manufacture, a heater comprising a casing having relatively thin walls, a cover, means for securing the cover in position on the casing and a cartridge adapted to be placed in the casing and comprising a wrapper of porous material, a filling of unslaked lime, and a plurality of bands in spaced positions extending around said cartridge and dividing the same into sections so as to prevent the 100

expansion of the cartridge beyond predetermined limits and to maintain the same in substantially cylindrical form while in use so that it may be readily removed after use

5 from the receptacle.

3. As a new article of manufacture, a heating cartridge comprising a cylindrical wrapper of porous material, a filling of unslaked lime and a plurality of bands applied
10 relatively loosely to the said wrapper in spaced positions to prevent the lime in the

slaking thereof from expanding the cartridge beyond predetermined limits and thus maintaining the cartridge in substantially its cylindrical form.

15

In testimony whereof I have affixed my signature in presence of two witnesses.

HORACE TURRETTINI.

Witnesses:

ELMER SCHMID,
ROD. DE WURSTENBERG.
